UNITED STATES PATENT OFFICE

2,608,049

COMBINATION RING WATCH

Sandor Alexander Wittmayer, New York, N. Y.

Application February 8, 1946, Serial No. 646,425

3 Claims. (Cl. 58—88)

1

This invention particularly relates to rings carrying watches, for an ornament and for useful purposes, and has for its main object to provide a combination jewelry of the type indicated which will have a novel construction and novel aesthetic appearance.

Another object of this invention is to provide a ring with a watch thereon wherein the watch dial normally will be concealed and wherein the same may be exposed for reading it, and again concealed, in an efficient manner.

Still a further object of this invention is to provide a ring watch wherein novel means are provided to normally conceal the winding crown for the watch, said concealing means being part of the ring design and being adapted to be easily opened when it is desired to wind up the watch.

My invention also relates to jewelry, in general, wherein a container, casing, or compartment is provided, as mentioned hereinbefore relating to a casing for watch, and which container, etc., will have novel, efficient and attractive means to close or to open it, as desired.

Still other objects of my invention will be apparent as the specification of the same proceeds.

In the drawings forming part of this specification and accompanying the same:

Fig. 1 is a plan view of the preferred embodiment of my invention as applied to ring-watch, the concealing top cover of the same having been moved into an open position disclosing the watch dial;

Fig. 2 is a side view of my ring-watch in a closed position, the upper part of the same being shown in section;

Fig. 3 is a partly sectional and partly elevational view, as indicated by the line 3—3 of Fig. 1;

Fig. 4 shows a fragmentary detail.

Fig. 5 is another plan view showing my device in a closed position;

Fig. 6 is a perspective view of a modification.

Referring to the drawings more in detail, by characters of reference, the numeral 10 indicates my ring watch, in general, being composed of the ring proper 11, the upper part 12 of which is formed into a watch receiving casing wherein is arranged the second part of my device, the watch movement 13. As will be seen by observing the drawings, the upper portion 12 of the ring is of a desired design and has the cylindrical recess 14 adapted to receive the watch movement 13 which may be secured therein in a movable manner by means well known in this art, or, simply by frictional action.

The watch movement 13 has an upper dial sur-

2

face 15, and the cover 16, in the embodiment shown being in the form of a spherical segment, is provided for normally concealing the watch movement with its dial and completing the aesthetic design and appearance of the ring, said cover 16 being horizontally rotatable or swingable on a pin 17 in the watch casing, as will be understood by those versed in this art.

It will be seen that when it is desired to read the watch in the ring the swingable cover 16 will be rotated on the pin 17 as indicated by the arrow 18, and when it is desired to conceal the watch dial, cover 16 will be rotated in the reverse direction until it completely covers the watch movement and fits into the general design of the ring, as indicated in Figs. 2 and 5.

To aid in both, the opening and the closing movements, a spring device, generally indicated by the numeral 21, is arranged within the cover 16. In the form shown in the drawing said spring device has a wire spring 22 one end 23 of which is secured into the watch casing and it is fixed, in position but rotatable, as by simply placing said end into a hole in the watch casing. The other end 24 is secured to the cover 16.

The securing of said end 24 to the cover 16 preferably is done in the manner indicated in the drawings, and it is shown more in detail in Fig. 4 which is a fragmentary inside view of the cover 16 at the place of such securing as indicated by the arrow 4 in Fig. 2.

It will be seen that a pin 25 is secured in the cover 16, pointing inwardly thereof, and a rotatable tube or sleeve 26 is arranged around said pin. A second sleeve or tube 27 is secured on said first sleeve 26 transversely thereof and the end 24 of the spring 22 will be drawn through said transverse tube or sleeve 27. The end 24 of the wire spring is slidable in the tube 27, and an enlargement 28 may be provided at its termination outside of the tube 27 whereby a sliding thereof entirely out of the sleeve 27 will be prevented.

Upon observing closely the operation of the spring 22 it will be seen that first the spring will have a tendency to keep the cover 16 closed when in such position. Upon pushing or sliding the cover sideways out of the closing position against the resistance of the spring (arrow 18), a certain intermediate neutral position will be reached after which the spring will aid in the opening movement until it will be fully expanded, as shown in Fig. 1.

In the opening movement of (arrow 18 in Figs. 1 and 5) the moving end 24 of the spring will at first be pressed closer to the fixed end 23 the

spring resisting such compression. After said neutral position the spring is permitted to expand aiding the opening movement.

When the cover 16 is again moved into a closing position from an open one, and it is being moved horizontally oppositely to the arrow 18, it will be seen that the spring, again, first will oppose such a movement but after a neutral position is passed, the spring will aid in the closing movement and will speed the cover into the closed position indicated in Figs. 2 and 5, the spring again taking up its full normal outline, as shown in Figs. 1 and 5.

In the embodiment of my invention shown in the drawings, I indicate novel attractive means to conceal the winding crown of the watch movement when the cover is closed, and to expose it by opening the cover when it is desired to wind up the watch. As will be seen from the drawings, right hand and left hand enlarged ornamental portions 29 and 30 are arranged at the upper ends of the ring 11, and a desired upper portion 29a of the right hand ornament is made separate from the rest of such ornament, and may preferably be secured on the adjacent portion 16a of the cover 16 so as to be movable therewith. It will be seen that when the cover or hood is moved into an open position, it will carry the upper portion 29a of the crown concealing ornament with it, exposing the crown 31 of the watch, as shown in Fig. 1.

A depending element 32 may be added on the movable portion 29a of the crown concealing hollow ornament 29, and a registering recess 33 provided in the fixed portion 29b of said ornament, the engagement of element 32 in said recess serving as a limit for the closing movement of the watch cover 16.

My experience has been that the spring, when the device is open, will ultimately lean against the pivot pin 17 of the cover 16. Said pin in this manner provides an outer limit for the opening motion of the spring (Fig. 1).

In Fig. 6 a modified form of my invention is shown. The general arrangement, object, and purpose remain substantially the same as in the embodiment of Figs. 1 to 5, and the respective parts have been identified with the same numerals, but in this embodiment a hinged member 40 is used to normally conceal the crown of the watch (not shown). Member 40 is swingable on pin 41 and in the normal position of it, as shown in Fig. 6, it will conceal the crown of the watch for which purpose it may be made hollow, as will be understood.

However, upon swinging member 40 outwardly, as indicated by the arrow 42, the crown of the watch will be revealed and the watch may be wound up. Member 40, obviously, may be designed as a movable part of the general design of the watch ring, as will be obvious to those versed in this art.

Member 40 also may be used as an inner stop and limit for the movement of the cover or top 16. For this purpose it may have a hole or recess 43, which when the watch is closed, will be engaged by a pin 44 on a stop member 45 secured on the cover 16.

It also will be understood, that while I have shown a preferred embodiment of my invention, changes and variations may be resorted to

in the elements, constructions and combinations thereof, and I want to reserve my rights to all such changes and variations which are within the spirit of this specification and the scope of the claims appended.

What I claim as new and want to protect by Letters Patent of the United States is:

1. In a piece of jewelry, having a portion formed into a receptacle, and a cover for said receptacle, adapted to be opened from or closed on the same, resilient means having a tendency to initially oppose either movement of said cover, when it is being opened or when it is being closed, a pivot for said cover on which

10 it may swing in its plane, said resilient means comprising an arcuate elongated spring in said cover, its inner end being secured on said piece of jewelry and its outer end on said cover, said securing of the outer spring end being in the 15 form of a pin in said cover, a sleeve rotatable on said pin, a second sleeve secured substantially transversely on said first sleeve, said spring end being slidably received in said second sleeve.

2. In a piece of jewelry, having a portion formed into a receptacle, and a cover for said

25 receptacle, adapted to be opened from or closed on the same, resilient means having a tendency to initially oppose either movements of said cover, when it is being opened or when it is being closed, a pivot for said cover on which it may swing in its plane, said resilient means comprising an arcuate elongated spring in said cover, its inner end being secured on said piece of jewelry and its outer end on said cover, said pivot serving as a limit for the outward opening movement of said spring and cover.

3. In a piece of jewelry, having a portion formed into a receptacle, and a cover for said

40 receptacle, adapted to be opened from or closed on the same, resilient means having a tendency to initially oppose either movements of said cover, when it is being opened or when it is being closed, a pivot for said cover on which it may swing in its plane, said resilient means comprising an arcuate elongated spring in said cover, its inner end being secured on said piece of jewelry and its outer end on said cover, a depending element on said cover and a recess in said piece of jewelry adapted to receive said element and thereby to serve as the limit for the inward closing movement of said cover.

SANDOR ALEXANDER WITTMAYER.
